SANITARY CHAIR ARM REST

Filed Oct. 7, 1944

UNITED STATES PATENT OFFICE

2,445,870

SANITARY CHAIR ARMREST

Clarence G. Maxson, Rochester, N. Y., assignor to
 Ritter Company, Inc., Rochester, N. Y., a corporation of Delaware

Application October 7, 1944, Serial No. 557,569

4 Claims. (Cl. 155—198)

1

This invention relates to arm rests for dental and medical operating chairs, one object being to provide an improved arm rest having more efficient and sanitary construction.

Another object is to provide an arm rest of the character indicated having combined therewith a sterilizing means, such as a source of germicidal rays and constructed in such a way as to be capable of being continuously sterilized while in position on the chair.

A further object is to provide such an arm rest arranged for progressively sterilizing the portion supporting the arm after each use thereof and without removal from the chair.

To these and other ends the invention resides in certain improvements and combinations of parts, all as will be hereinafter more fully described, the novel features being pointed out in the claims at the end of the specification.

In the drawings:

Fig. 1 is a side elevation of a portion of an operating chair having the present invention applied thereto;

Fig. 2 is an enlarged elevation, partially in section, on the line 2a—2a in Fig. 3;

Fig. 3 is an enlarged section on the line 3a—3a in Fig. 2, partly broken away; and

Fig. 4 is an enlarged elevation corresponding to a portion of Fig. 2 but with additional parts in section.

The embodiment of the invention herein described, by way of illustration, is shown as adapted for application to a chair of known construction for dental and medical operating use, comprising a seat 10 on a frame 11 mounted on a pedestal 12. Pivottally connected to the seat frame as at 13 and 14, is an adjustable back portion 15 of any known and suitable construction which forms no part of the present invention and so requires no description in detail.

The present invention preferably comprises an arm rest support in the form of a standard 16 adjustably fixed at its lower end on the seat frame 11 as by means of a clamping bail 17. Standard 16 is preferably bifurcated at its upper end to provide branching arms 18 and 19 on the spaced ends of which the arm rest 20 is mounted. As the arm rest is the same for each side of the chair, of course, a description of one will suffice for both.

The arm rest comprises, preferably, a metal casing 21 of elongated channel shape with its open side disposed upwardly, as shown. The casing is conveniently made, in the present instance, of a one-piece, channel shaped body portion 22,

2

the upper side edges of which are preferably rolled and stiffened as at 23. The ends of portion 22 are preferably seated within flanges 24 formed on end plates 25 and 26 which form the ends of the casing.

The arm supporting member proper is preferably an elongated solid member, or bar, 27, having opposite, lateral, arm receiving portions or surfaces, 28 and 29, suitably curved to comfortably engage and support the arm of the occupant of the chair. The other opposite sides of member 27 are preferably fluted as shown at 30, although it will be appreciated that the particular cross sectional shape may be varied as desired.

15 Arm rest member 27 is located and movably mounted in the described opening at the top of casing 21, so as to closely engage the side and end walls and close the opening, as shown. To this end, member 27 preferably has each end

20 thereof formed with a concentric bore 31 in which a stud 32 is secured by a driving fit, the stud being formed with knurled portions 33, if desired, to more securely fix it in the member 27. Each of these studs 32 has a cylindrical section 34 immediately beyond the end of member 27 and this section is rotatably mounted in a bearing opening 35 in the adjacent end wall of the casing, thus supporting the arm rest member 27 for rotation in the casing opening.

25 Housed within each casing 21 is a sterilizing means, preferably in the form of an elongated source of germicidal rays, such as one of the known mercury vapor, gaseous conduction tubular lamps 36, although any other suitable source 30 of ultra violet rays may be employed in the casing for germicidal treatment of the arm rest surfaces. In the present instance, casing 21 contains at each end thereof a supporting socket means 37, of any known and suitable construction,

40 in which the usual contact pins at the ends of the lamp tube 36 are received and engaged by contacts, for closing and energizing the circuit through the tube, as well understood in the art.

45 This circuit includes any known and suitable controlling means which may be located on the chair or at some distant point. It will be seen from Figs. 3 and 4 that the several parts are so associated and arranged that the arm supporting surface 29 is subjected to direct treatment by sterilizing rays from the lamp while the opposite surface 28 is disposed in arm supporting position. Member 27 may be constructed of plastic, glass, or other known material adapted for the purposes indicated, including the obstruction of the

ultra violet rays so as to prevent them from escaping from casing 21.

Means are preferably provided for retaining arm rest member 27 in each of its adjusted positions, comprising, in the present instance, a circular disk 38 fixed on one of the trunnions 34 of the arm rest member 27. For this purpose, the trunnion projecting outwardly through the end 25 of casing 21 is formed with an angular or square section 39 which is received in a correspondingly angular opening in disk 38, the latter being held on the stud as by means of a cap screw 40. Disk 38 is equipped at oppositely spaced points with openings 41 in which a pair of spools 42 are slidably retained. The outer head of each spool is large enough to be conveniently grasped in the fingers, while its reduced inner head slides in the enlarged inner end 43 of the spool receiving opening 41. Fixed in the casing head 25 is a socket tube 44 in which a cylindrical plunger 45 is slidably housed and pressed outwardly by a coiled compression spring 46 within the tube, as shown. As disk 38 is rotated to bring one of the spools 42 opposite the plunger 45, the latter is projected into the enlarged end 43 of the spool receiving opening 41, thus retaining the disk and arm rest member 27 in adjusted position. To release the disk for adjustment, the lower spool is pushed in to push back the plunger 45 and thus release the disk for turning by means of the spool as a handle.

The operation of the device will be apparent from the above description of its construction. After use of one of the arm receiving surfaces, as 28, the lower spool 42 of disk 38 is pressed inwardly to eject detent plunger 45 from the spool receiving opening, thereby freeing disk 38 for rotation through 180 degrees, whereby the opposite spool of the disk is brought opposite the detent plunger which thereupon springs into its opening in the disk and yieldably locks the disk in a position to locate the used surface 28 in the casing and replace it by the surface 29 previously sterilized by subjection to the germicidal rays from the lamp source 36. The used surface 28 is thus brought to position for sterilization in the casing in preparation for a repetition of the cycle.

In this convenient and effective way, the invention provides for progressive sterilization of the arm rest surfaces as they are successively subjected to use, without removal from the chair which is at all times maintained, therefore, with sterilized and sanitary surfaces for the arms and hands of the patient. The invention is embodied, furthermore, in a simple and practical type of construction capable of being readily and economically manufactured and assembled on the chair.

It will thus be seen that the invention accomplishes its objects and while it has been herein described by reference to the details of a preferred embodiment, it is to be understood that such disclosure is intended as illustrative, rather than in a limiting sense, as it is contemplated that various changes in the construction and arrangement of the parts will readily occur to those skilled in the art, within the spirit of the invention and the scope of the appended claims.

I claim:

1. A sanitary arm rest for dental and medical operating chairs comprising a casing having an opening therein, means for supporting said casing at one side of said chair in position for supporting an arm of an occupant thereof, a source of germicidal rays in said casing, and an elongated

unitary arm supporting member rotatably mounted on said casing in said opening thereof with one portion thereof normally disposed outside said casing in position for engagement with the arm of an occupant of the chair and also with another portion located inside said casing and exposed to germicidal treatment by said rays, said member being rotatable on said casing to alternately rotate said portions thereof directly to position for supporting engagement with an occupant's arm and to position for exposure to said rays, respectively.

2. A sanitary arm rest for dental and medical operating chairs comprising a casing having an opening in a wall thereof, means for supporting said casing at one side of said chair in position for supporting an arm of an occupant thereof, a source of germicidal rays in said casing and a unitary elongated arm supporting member movably mounted on said casing in said opening thereof with one portion thereof normally disposed outside said opening in position for engagement with the arm of an occupant of said chair and also with another portion thereof inside said casing and exposed to germicidal treatment by said rays, said member being movable in said opening to alternately move said portions thereof directly to position for supporting engagement with an occupant's arm and to position for exposure to said rays, respectively.

3. A sanitary arm rest for dental and medical operating chairs comprising a casing having an opening in a wall thereof, a support provided with means for attachment to the seat of a chair for supporting said casing at one side of said chair in position for supporting an arm of an occupant thereof, a source of germicidal rays in said casing, and a unitary elongated arm supporting member rotatably mounted in and closing said casing opening with one integral portion thereof normally disposed outside said casing in position for engagement with the arm of an occupant of the chair and also with another integral portion thereof inside said casing and exposed to germicidal treatment by said rays, said member being rotatable in said opening to alternately rotate said portions thereof directly to position for supporting engagement with an occupant's arm and to position for exposure to said rays, respectively.

4. A sanitary arm rest for dental and medical operating chairs comprising a casing having an opening therein, a support provided with means for attachment to the seat of a chair for supporting said casing at one side of said chair in position for supporting an arm of an occupant thereof, a source of germicidal rays in said casing, a unitary elongated arm supporting member located in and closing said casing opening, said member having its ends rotatably mounted on said casing with one integral portion of said member normally disposed outside said casing opening in position for engagement with the arm of an occupant of the chair and also with another integral portion thereof inside said casing and exposed to germicidal treatment by said rays, said member being rotatable in said opening to alternately rotate said portions thereof directly to position for supporting engagement with an occupant's arm and to position for exposure to said rays, respectively, to maintain said member in sterile condition, and means for retaining said member in adjusted position.

CLARENCE G. MAXSON.
